CLAIM

The ornamental design for the combination ratchet and brake-bar, as shown and described.

DESCRIPTION

FIG. 1 is a perspective view of the design of the present invention.

FIG. 2 is a front view of the design of the present invention.

FIG. 3 is a rear view of the design of the present invention.

FIG. 4 is an elevation view of the design of the present invention.

FIG. 5 is the opposite elevation view of the design of the present invention.

FIG. 6 is a top view of the design of the present invention, enlarged with respect to the prior views for clarity; and,

FIG. 7 is a bottom view of the design of the present invention, enlarged with respect to the prior views for clarity.
